LAMP

Victor D. Milanese and Pietro A. Pascale,
Masury, Ohio

Application May 4, 1954, Serial No. 30,323

Term of patent 7 years

(Cl. D48—20)

To all whom it may concern:

Be it known that we, Victor D. Milanese and Pietro A. Pascale, citizens of the United States of America, residing at 29 Lucy Street, Masury, Ohio, and 81 W. State Street, Masury, Ohio, respectively, have invented a new, original, and ornamental Design for a Lamp, of which the following is a specification, reference being had to the accompanying drawing, forming a part hereof.

The single figure is a perspective view of a lamp showing our new design.

We claim:

The ornamental design for a lamp, as shown.

No references cited.
